UNITED STATES PATENT OFFICE.

EDGAR HENNIGAR, OF PORTLAND, MAINE.

OPEN STOVE AND FIREPLACE.

No. 790,881.

Specification of Letters Patent.

Patented Aug. 1, 1905.

Application filed January 23, 1905. Serial No. 242,211.

To all whom it may concern:

Be it known that I, EDGAR HENNIGAR, a subject of the King of Great Britain, residing in Portland, in the county of Cumberland and State of Maine, have invented a new and useful Improvement in Open Stoves and Fireplaces, of which the following is a specification.

This invention relates to that class of stoves or fireplaces termed "open" or "open-grate" stoves or fireplaces. In other words, it relates to stoves considered as portable structures and fireplaces considered as stationary structures, the construction of which is substantially the same in both instances, both being adapted to accommodate open fires.

In my invention I provide a deflector or substantially horizontal guard at a point high above the bed or base, but with its entire top or upper surface at a level which is sufficiently below the top or mantel to produce a horizontal inward draft high above the fire, but well below the top or mantel, the deflector projecting far enough forward over the fire to prevent the cold air from falling and to force the hot air and smoke from the fire forward until it is caught by the horizontal draft of cold air and guided over the top of the deflector and thence into the chimney-flue.

The principal object of the invention is to prevent the fire from smoking.

The nature of the invention is fully described below and illustrated in the accompanying drawings, in which—

Figure 1 is a front elevation of a fireplace or stove embodying my invention. Fig. 2 is a central vertical section of the same. Fig. 3 is a similar section showing a modification.

Similar letters of reference indicate corresponding parts.

a represents the floor or bed of the fireplace or open stove, no grate being shown, as the grate forms no part of the invention.

b is the rear wall.

c is the top or mantel.

d is an upwardly-extending flue which leads to the chimney or which may be in the chimney.

The rear wall is deflected forward at *e* into the fireplace or stove over the fire until it constitutes the deflector *g*, said deflector bending rearward at *h* on a substantially horizontal

line and the rear wall extending upward at *k* and constituting in connection with the front wall *l* the walls of the upwardly-extending flue *d*, which extends into and may be a part of the chimney. The entire length and width of the top *h* of the deflector are at a level which is well below the level of the shelf *c*.

In practice the cool air from the room approaches the horizontal passage above the deflector in a substantially horizontal line at a point high above the fire and passes horizontally between the level of the shelf *c* and the top wall *h* and is then deflected up into the flue *d* and into the chimney. As this draft of cool air enters the horizontal passage between the shelf *c* and the part *h* it catches and carries with it the hot air and smoke from the fire which is at that point and has been carried forward by the deflector. Downdraft is prevented, so that the cold air cannot drop to the fire, and thus smoking of the fire is obviated.

In Fig. 3 the deflector is not an integral portion of the rear wall, but consists of a separate piece *s*, secured to said rear wall in the same position and approximately in the same shape as the deflector *g* and with substantially the same effect.

Having thus fully described my invention, what I claim, and desire to secure by Letters Patent, is—

In an open stove or fireplace, the forwardly-extending horizontal top or mantel *c*; the vertical wall *l* extending up from the mantel, and the rear vertical wall *k*, whereby a vertical flue *d* is produced between said walls; and the deflector consisting of the substantially horizontal top wall *h* located below the mantel, and the forwardly-extending wall *e*, whereby a horizontal passage or flue is produced next and below the mantel, said passage or flue occupying the entire space between the wall *h* of the deflector and the mantel, and connecting directly with the said vertical flue, substantially as set forth.

In testimony whereof I have signed my name to this specification in the presence of two subscribing witnesses.

EDGAR HENNIGAR.
